CONDUIT BLOCK MAKING APPARATUS

Russell M. La Due, Sioux City, Iowa

Application March 14, 1932. Serial No. 598,722

3 Claims. (Cl. 25—36)

An object of my invention is to provide a conduit block making apparatus of simple, durable and comparatively inexpensive construction.

More particularly, it is my object to provide a machine for forming cement blocks with a plurality of ducts therein.

A further object is to provide a plurality of packer head assembly elements arranged to form ducts in a cement block during the forming of the block, which packer head assemblies are operated by means of driven shafts operatively connected together and synchronized so that projections on each packer head assembly will travel symmetrically with respect to the next adjacent packer head assembly.

With these and other objects in view my invention consists in the construction, arrangement and combination of the various parts of my device, whereby the objects contemplated are attained, as hereinafter more fully set forth, pointed out in my claims and illustrated in the accompanying drawing, in which:

Figure 1 is a front plan view of a machine frame illustrating a plurality of driven shafts with my packer head elements arranged at the lower end of each shaft.

Figure 2 is a sectional view taken on the line 2—2 of Figure 1 illustrating the packer head assembly in section within a conduit block.

Figure 3 is a similar view of two adjacent packer head assemblies in a position slightly different from the position shown in Figure 2.

Figure 4 is a diagrammatic view illustrating a train of gearings for driving the packer head carrying shafts.

Figure 5 is a diagrammatic view illustrating the packer head assemblies arranged in a plurality of rows; and

Figure 6 is a perspective view of a cement conduit block made with my machine.

On the accompanying drawing I have used the reference character A to indicate generally a frame having a top bearing 10 and an intermediate bearing 12. A plurality of driven shafts 14, 16, 18 and 20 are illustrated as mounted within the frame A. The shafts 14, 16, 18 and 20 have gears 22, 24, 26, and 28 mounted thereon respectively. The gears 22, 24, 26, and 28 are in mesh with each other as clearly illustrated in Figure 4. A gear 30 is mounted on a suitable shaft 32 driven from a source of power. An intermediate gear 34 on the shaft 36 connects the gear 30 with the gear 24 so that the train of gears just described and as illustrated in Figure 4 rotate in the direction indicated by the arrows C shown upon each gear. The

shafts 14, 16, 18 and 20 rotate in the direction indicated by the arrows shown upon their respective gears. The shafts 14, 16, 18 and 20 are capable of vertical movement relative to their respective driving gears.

Placed adjacent to the frame A is a mold 38, formed in any suitable manner, and having a substantially rectangular cross sectional outline. The mold is of the size and shape to form the block shown in Figure 6.

In order to provide a plurality of ducts 40 in the block B, I provide packer head assemblies C shown upon the bottom of each of the shafts 14, 16, 18 and 20.

Each packer head assembly C includes a cylindrical trowel member 42 and a pair of oppositely spaced wing cheeks 44. The wing cheeks 44 are bolted or otherwise secured to each shaft upon flattened portions formed thereon. The wing cheeks 44 are positioned just above the trowel members 42. A chute 46 is employed for running cement into the mold 38.

When the cement first enters the member 38 the packer head assembly is at its lowermost position. After the packer head assemblies are rotated in opposite directions as has heretofore been described and the wing cheeks serve to pack the cement and the trowel members therebelow serve to finish the duct and as the packer head assemblies move upwardly they leave within the block well defined and finished ducts.

The packer head assemblies operate and rotate in opposite directions with the wing cheeks 44 positioned so that the wing cheeks of any two adjacent packer head assemblies are symmetrically arranged.

It will be noted from Figure 3 that the two adjacent wing cheeks are in exactly the same position relative to the cement block. As the packer head assemblies having wing cheeks as a part thereof rotate in the directions indicated by the arrows 46 they are brought into positions relative to the material adjacent the two ducts as at 50 wherein one packer head serves as a wall against which the pressure exerted by the next adjacent packer head exerts its force. Each packer head serves to prevent the material as at 50 from collapsing or breaking down during the manufacture of the cement blocks. In making blocks out of cement and packing them so as to provide ducts therein, it is necessary that the material be packed against some wall-like object and I employ the next adjacent packer head assembly to take up the force of the opposite wing cheek so that practically each packer head assembly re-

volves within a mass of cement-like material as though a complete mold enclosed each packer head assembly and as though only one duct was being made within the block.

5 It will be noted that the packer head assemblies all revolve in opposite directions and that they are synchronized so that the wing cheeks are positioned to meet and register correctly one to another and this is true irrespective of the number of rows of ducts that may be made.

I have illustrated in Figure 2 the use of four packer heads to make a four duct block and it will be understood that the number may be varied, that is two or more.

15 In Figure 5, I have illustrated two rows of ducts with three in each row. The number of rows may be varied and it is only necessary, in order to keep the material between the ducts from collapsing, to have the packer heads operate in opposite directions, although synchronized as to position of the wing cheeks upon each packer head.

Some changes may be made in the construction and arrangement of the parts of my device

25 without departing from the real spirit and purpose of my invention, and it is my intention to cover by my claims, any modified forms of structure or use of mechanical equivalents which may be reasonably included within their scope.

30 I claim as my invention:—

1. A concrete conduit forming apparatus comprising a plurality of driven shafts, gearing between said shafts for driving them in opposite directions, a packer head assembly upon each shaft, a pair of opposite packing wings on each

packer head assembly, the packing wings of each packer head assembly being operatively connected with the next adjacent packer head assembly so that the packing wing of one assembly is directly opposite the packing wing of the next adjacent assembly when they pass the thinnest part of the wall between adjacent conduit openings and thereby prevent collapsing of the concrete in said thinnest part of the wall.

2. In an apparatus for making a concrete conduit having a plurality of substantially parallel ducts, a mold, a plurality of shafts, a packer head on each shaft, a packer wing on each packer head, means for imparting rotation and longitudinal movement to said shafts and said packer heads and means for synchronizing the rotation of said packer heads so that said wings are directly opposite each other when in said mold and adjacent the thinnest part of the wall of a conduit being formed by said packer heads and for synchronizing the longitudinal movement of said packer heads so that said wings are continuously opposite each other throughout such longitudinal movement.

3. In an apparatus for making a concrete conduit having a plurality of substantially parallel ducts, a mold, a plurality of shafts, a packer head on each shaft, a packer wing on each packer head, means for imparting rotation and means for synchronizing the rotation of said packer heads so that said wings are directly opposite each other when in said mold and adjacent the thinnest part of the wall of a conduit being formed by said packer heads.
